UNITED STATES PATENT OFFICE

DEWEY E. GOMMEL, OF INDIANAPOLIS, INDIANA, ASSIGNOR TO E. C. ATKINS & COMPANY, OF INDIANAPOLIS, INDIANA, A CORPORATION OF INDIANA

SAW SWAGE

Application filed April 17, 1930. Serial No. 445,144.

This invention relates to improvements in saw swages and more particularly is an improvement on swages such as that shown in my co-pending application Serial No. 5 299,414, filed August 13, 1928, for saw swages.

An object of this invention is to provide means for more securely holding the parts of the swage to prevent them from getting out of adjustment during swaging operation.

A further general object is to provide a swage which will be more accurate during swaging operation.

Referring to the accompanying drawing, 15 which is made a part hereof and on which similar reference characters indicate similar parts,

Figure 1 is a side elevation of a saw swage having my invention embodied therein, and 20 Figure 2 is an end elevation of one of the details of the device.

In the drawing numeral 10 indicates a swage block which is cylindrical in shape and which has mounted therein a swaging 25 die 11 which is operated by means of a lever 12 which is suitably secured to one end of the die 11. A lever 13 operates a screw, not shown, to hold the block 10 securely upon a saw 14. A swaging anvil, not shown, is held 30 against and adjusted by a screw 15. Numeral 16 indicates a supporting frame upon which the swaging block is mounted. This frame has at one end a supporting standard 17 which is secured to the end of the frame 18 by means of a screw 19 which passes through a slot 19 in the support 17. The lower end of the support 17 has a flat bar 20 which rests upon the tips of the saw teeth, preferably extending over two or more teeth as shown. 35 A support 21 is secured to the other end of the frame 16 by means of a bolt 22 which passes through a slot 23 in the support 21 and a slot 24 in the end 38 of the frame 16. 40

A horizontal flat bar 25 is secured to the support 21 so as to rest on the tips of the saw teeth. The support 21 has prongs 26 which straddle the saw. A bracket 27 is secured to the block 10 by means of a bolt 28, the bolt passing through a slot 29 in an arcuate portion 30 of the frame 16. The bracket 45

27 carries an adjustable stop 31 to limit movement of the lever 12 in the direction of swaging a tooth. A stop 32 is secured to the end of the frame 16 to limit movement of the lever 12 in the opposite direction. The 55 position of the swaging die anvil with respect to the back of the saw tooth 33 is determined by the position of the die block 10 with respect to the frame 16. This adjustment is for different forms of teeth. Positions of stops 31 and 32 and anvil 15 regulate the swage. This adjustment of bracket 27 is for back clearance on teeth from 10° to 40° variation.

During a swaging operation the lever 12 necessarily is brought to strike against the stop 31. This tends to rotate the block 10 counterclockwise and it has been found very difficult to secure the bolt 28 tight enough to prevent the block 34 which is positioned on top of the arcuate portion 30 of the bracket from slipping toward the left. In order to prevent this slipping I have made the arcuate portion 30 thicker at one end than at the other so as to provide a wedging action. That is, the distance between the outer and inner arcs of the arcuate portion 30 is greater at one end than at the other, for example, in a small swage the distance at the right end might be $\frac{1}{16}$ ths of an inch, as shown, with the 75 distance at the left hand end $\frac{11}{32}$ ths of an inch, as shown. This difference in thickness is sufficient to cause a very accurate wedging action between the block 10 and the arcuate block 34 so that the block 34 is prevented 80 from sliding toward the left in a counterclockwise direction. A very little movement to the left will tighten the block so that it will soon become secured against further movement.

During a swaging operation since the force acting on the lever 12 is toward the left, as shown in Figure 1, there will be a tendency for the end 38 of the frame 16 to slide down in the slot 23 on the support 21. In order to prevent such sliding after the end of the frame 16 is adjusted in the slot 23 I make the upper portion 35 of the support 21 a little thinner than the lower portion 36 so as to provide a wedging action between 85 a washer 37 of the bolt 22 and the end 38

of the frame 16. This difference in thickness may be in the nature of $\frac{1}{2}$ " for example for a swage of the size described. The top of the support 21 may be $\frac{8}{32}$ " and the lower portion at 36 may be $\frac{9}{32}$ ". This difference in thickness provides a wedging action between the ends 38 of the frame and the washer 37. Since one side of the support 21 must fit evenly against the face of the end of the frame 16, I make only one side of the support tapered. It should be noted that only the right surface 39 is tapered upwardly.

It will be obvious to those skilled in the art that various changes may be made in my device without departing from the spirit of the invention and therefore I do not limit myself to what is shown in the drawing and described in the specification, but only as indicated in the appended claims.

Having thus fully described my said invention, what I claim as new and desire to secure by Letters Patent, is:

1. A saw swaging device comprising a frame having a block mounted therein, a swaging die mounted in the block, a lever for operating the die, arms on said frame for holding it on a saw, one of the arms having a depending leg engageable with the saw, said depending leg having means for adjustably attaching it to the said arm, said leg gradually increasing in thickness from its upper end toward the center, providing a wedging action between it and the attaching means whereby any slippage of the arm on the leg will tend to tighten the engagement between the leg and the arm to prevent further slippage, substantially as set forth.
2. A swaging device comprising a frame, a swaging block rotatably mounted in the frame, a swaging die carried by the said block, an anvil in the said block engageable with a saw tooth in position opposite to the said die, a lever for rotating said die, a bracket secured to the said block, an arcuate portion on the said frame engageable by the said block, said arcuate portion having a progressively increasing thickness to tighten the block against rotation as it tends to rotate beyond a predetermined distance, substantially as set forth.

In witness whereof, I have hereunto set my hand and seal at Indianapolis, Indiana, this 15th day of April, A. D. nineteen hundred and thirty.

DEWEY E. GOMMEL.
